UNITED STATES PATENT OFFICE

BENJAMIN W. FREEMAN, OF CINCINNATI, OHIO

ART AND METHOD OF MAKING SHOES

Application filed January 25, 1927. Serial No. 163,515.

My invention relates to methods of forming and fastening the bottoms of shoes, and more particularly to methods of forming and fastening the heel portions of the sole to shoes which are to have wooden heels. The invention relates to a novel method of making shoes in which attaching the heel to a shoe has a co-operative effect on the method of forming and attaching the sole.

One of the objects of my invention is to provide a process which will eliminate the costly hand labor required in the heel seating or rand shaping operation preparatory to the attachment of wood heels, which requires the hand labor of a highly skilled operator. With the elimination of that part of a sole which has a rand portion it is my object to provide means of securing the sole adjacent the heel breast securely as a shoe bottom. Other advantages of my new method such as the saving in material required will be noted during the course of the ensuing disclosure.

The use of the short outsole has been suggested at various times but no one has ever produced a method such as the one herein disclosed which is adapted for use in the commercial production of shoes. The objects of heretofore known methods have been the saving of sole leather and alleged advantages in other than in the sole fitting operation, and while these several developments have suggested short outsoles formed for registry with the heels, they have never disclosed or suggested any practical principle of shoe manufacture to avoid in a practical and useful manner the expensive labor of heel seat fitting. Further, no one has provided a method adapted for use in the making of shoes having wooden heels. My novel method of making shoes has as its object the saving effected in the heel seating operation and my method produces a commercially salable product. To the best of my knowledge and belief no one has previously devised a method or made possible such economies in the manufacture of shoes, particularly where wooden heels are used, as I contemplate.

Referring to the drawings in which I have illustrated several partially assembled shoe

parts showing the constructive principle involved:

Figure 1 is a bottom plan view of a partially assembled shoe illustrating the method of attaching the outsole of a shoe bottom. 55

Figure 2 is a section along the lines 2—2 in Figure 1.

Figure 3 is a section along the lines 3—3 in Figure 1.

Figure 4 is a longitudinal section through 60 the shoe at the heel end after the attachment of the heel.

Figure 5 is a plan view of a heel ready for attachment to the shoe bottom shown in Figure 1. 65

Figure 6 is an elevation from the breast end of the heel shown in Figure 4.

Figure 7 is a section along the lines 7—7 in Figure 6.

Considering the structures indicated at 70 Figures 1—7, I have shown a shoe of the turned type. I have shown the upper 1 attached to the ridge 2 of the outsole 3 with stitches 4. The shank is indicated at 5 and I have shown the shank reinforced with a metal plate 6. I preferably take the outsole piece 3 and cut with a machine driven die a tongue 7 at the heel end of the outsole. The shape of this tongue may be in accordance with any desired pattern. Since in the particular example of turned shoe shown I have elected to attach a wood heel having an 75 attaching surface contoured in accordance with standard practice at present, the tongue 80

7 will be preferably formed to conform to this contour. The wood heel indicated at 8, it will be noted, has a cup-shaped contoured attaching surface 9. It is usual to cover the heel 8 with soft leather, which is brought up over the attaching surface and tacked or cemented down to the edge portion of the heel, as indicated at 8a. I have shown in Figure 1 the broken line 10 indicating the edges of the upper in the heel portion of the shoe bottom, secured to the shoe bottom with the tacks 11. As the heel to be attached is of decidedly contoured base surface, I have provided a filling piece 12 which is shown in position in Figure 1 secured with the tacks 13. It will be obvious that when it is de- 85 90 95 100

sired to attach a filler piece, the contour of the base surface of the heel being known, it will be a simple matter to mold or press the filler piece with a like contour. The contouring of a filler piece prior to its attachment to the shoe bottom may be accomplished in a very short time, and the hand labor of cutting each heel seat subsequently to the attachment on the shoe bottom will thereby be eliminated.

For certain types of ladies' shoes, wood heels are almost essential. In the customary manufacture of shoes, the base of the heel should be concavely contoured because the heel seat portion at the time the heel is attached presents a convex surface. A further reason why shoes with wood heels require that the heels should have concaved bases is to enable the covering of the heel which usually has the same finish as the upper to make a snug joint at the meeting line between the heel and the upper. The sole of the shoe is normally of leather having peripheral edges which are rough and unfinished. If the sole was visible and could be seen interspacing the heel and the upper the appearance would be greatly marred. This was one of the reasons why shoemakers adopted a plan of extending the sole back under the heel and then cutting it off so that the outer peripheral edges of the base of the heel would practically abut the lower outer surface of the shoe upper. The finish of the shoe would then extend from the top of the heel to the top of the upper with no sole showing at the intersection of heel and upper. It is this structure which has required the heel seating operation which consists in cutting away the rand of the sole or that part which is cut away so that the edges of the base of the heel and the upper can meet. Therefore, the particular expensive step in the manufacture of shoes which I propose to make unnecessary relates specifically to shoes with wood heels. No problem of heel seating exists in the manufacture of shoes with leather or composition heels as the attachment of leather heels requires nothing more than the attachment of one surface to another, and the outer surface of the heel being finished to the same appearance as the outer surface of the sole, the necessity of cutting away the rand portion is not present.

I have shown the tongue 7 of the outsole tacked to the shank with a line of tacks 14, this being one of a number of methods which may be used for firmly securing the outsole so that there will be no tendency of the outsole to break away from the shoe bottom or open at the heel breast.

In forming the rear part of the outsole it is desirable to taper off the sole lying under the heel breast, as indicated at 14a, so that when the heel is attached it will tend to provide a firm interlock in the heel breast joint.

While I have shown one specific form as applied to a turned shoe the same plan of operation is applicable to other types such as welts, McKays or any of the special processed shoes.

I have shown the use of tacks as means for fastening the sole and filler although other means of bringing about this attachment will readily occur to those skilled in the art. It will be obvious that other means may be employed for holding the shoe parts mentioned in position. I have also shown the sole fastened to the leather portion of the shank. The sole might have been attached to the steel portion as, for example, by means of a rivet or rivets. Different combinations will be apparent to those skilled in the art as to the fastening and manner of fastening the rear portion of the outsole according to the class or type of shoe with which my method is employed. As no one previously has indicated any method of eliminating the present expensive method of heel seat fitting, and strengthening the attachment of the sole in the heel breast portion, I claim the same broadly herein.

For attaching the tongue 12 to the shoe bottom I have shown a structure in Figure 4 which will provide a firm interlock. This consists of a heel nail indicated at 14b which may be driven from within the shoe through the tongue and into the heel. Such nails may be inserted in other directions than that indicated or other means of fastening may be used.

I have illustrated only one kind of heel which is of military type. It will be within the range of mechanical skill to apply other type heels than those indicated in a similar manner. The various modifications in the methods of combining the heel end of the shoe bottom and the heel are adapted for use with those types of shoes wherein the breast cover of the heel is formed by a flap or lodge usually formed from the grain portion of the heel seat end of the sole.

It will be apparent that there are many modifications which will readily occur to those skilled in the art. The essential feature of my new method of making shoes lies in the entire avoidance of the present method of heel seating, and within the scope of those modifications which may be suggested by the method which I have described, I claim this art and method broadly.

Having thus described my invention what I claim as new and desire to secure by Letters Patent is:—

1. The method of making shoes with wood heels having concave bases, which comprises forming a short outsole for part of the shoe bottom, shaping a filler piece to fit within the concave base surface of a wood heel, and independently applying the filler piece to the shoe bottom and then applying the wood heel.

2. The steps in the making of shoes with wood heels having concave bases, which comprises making a shoe sole with a portion of the sole extending no farther under the attaching surface of a wood heel than may be required to form an inter-engagement between the edge of the outsole and the upper surface of the heel, attaching the extension to the shoe bottom, and providing a shaped filler piece and independently applying same to the shoe bottom to fit between the upper surface of the concavity of the heel and the shoe bottom.

3. The art of making shoes with wood heels having concave bases without a sole heel seat fitting operation, comprising the steps of using a short outsole, strengthening the attachment of the sole to the shoe adjacent the heel breast, and then applying a shaped filler piece to the shoe to fit the concave base of the heel.

4. The method of making shoes with wood heels having concave bases in such manner as to obviate the necessity of removing the rand from the heel portion of the sole as a wood heel seat fitting operation which comprises forming a short heel portion of an outsole to fit the base portion of a heel, said forming operation providing a sole extension beyond the heel breast line at each end of the heel breast line of the sole, to be pressed against the shoe by that portion of the heel adjacent the heel breast at the ends thereof, and fastening the sole adjacent the heel breast at the side edges of the heel breast, and independently applying a shaped filler piece to fit the concavity of the heel base.

5. The art of making shoes with wood heels having concave bases without a heel seat fitting operation, comprising the steps of using a short outsole, strengthening the attachment of the sole to the shoe adjacent the heel breast, and then applying the heel having a concave base with an independent filler piece, shaped to fit the concavity of the heel, secured between the concave base of the heel and the shoe bottom.

6. In the art of making shoes with wood heels having recessed bases, the steps of employing a short outsole having an extension overlapping under the attaching surface of a wood heel of the character specified, and providing a filler piece to complement the shape of said extension and form therewith a surface shaped to fit the recess of the attaching surface of the heel.

7. The steps in the making of shoes with wood heels having recessed bases which comprises making a shoe sole with a portion of the sole extending under the attaching surface of a wood heel so as to form an interlocking joint therewith between the extension of the sole and the attaching surface of the heel, and providing an independent

shaped filler piece to complement the shape of the sole extension and fill out the space within the recessed portion of the attaching surface of the heel and the shoe bottom.
